UNITED STATES PATENT OFFICE.

WILLIAM E. KELLY, OF NEW BRUNSWICK, NEW JERSEY.

GRATE-BAR.

SPECIFICATION forming part of Letters Patent No. 394,984, dated December 25, 1888.

Application filed August 23, 1888. Serial No. 283,590. (No model.)

To all whom it may concern:

Be it known that I, WILLIAM E. KELLY, of New Brunswick, in the county of Middlesex and State of New Jersey, have invented a certain new and useful Improvement in Grate-Bars, of which the following is a specification.

My improvement relates to grate-bars provided with detachable leaves.

- 10 The improvement consists, essentially, in the combination, with a grate-bar having its upper portion made of uniform width, but sinuous in a vertical direction, of a number of leaves having slots or openings, also made 15 sinuous in a vertical direction, so as to be adapted to interlock with the sinuous portion of the bar. The bar will preferably be provided with a straight portion, over which the leaves may be moved downwardly and from 20 which they may be slid laterally over the sinuous portion of the bar.

In the accompanying drawings, Figure 1 is a side view of a grate-bar embodying my improvement, some of the leaves being shown in 25 transverse section. Fig. 2 is a transverse vertical section taken at the plane of the dotted line $x x$, Fig. 1. Fig. 3 is a transverse vertical section taken at the plane of the dotted line $y y$, Fig. 1.

30 Similar letters of reference designate corresponding parts in all the figures.

A designates a grate-bar. It may be of any desired construction, strengthened with ribs $a' a^2$, or in any other approved style. It may 35 have trunnions at the ends. I have shown one such trunnion, a^3 . Adjacent to the trunnion I have shown an end flange or rib, a^4 .

B designates a number of leaves. These 40 may be of any desired configuration and construction, excepting as to the portion engaging with the bar A. The upper portion, a^5 , of the bar A is of uniform width, but is sinuous in a vertical direction, as may be best understood by reference to Fig. 3. As shown, 45 the upper portion, a^5 , curves first to one side and then to the other, or, in other words, is made with an upwardly-extending ogee curve. Any other sinuous shape may, however, suffice, and it is not necessary that the sinuosity 50 should be curved. The sinuous portion will,

however, be of substantially uniform width or thickness throughout its extent. Each of the leaves B has an opening, b , extending from the lower extremity upward. This opening will be made sinuous to correspond with the 55 sinuosity of the upper portion, a^5 , of the bar A. The upper sinuous portion, a^5 , of the bar A is so formed at one point in its length (in the present instance at the plane of the dotted line $x x$, Fig. 1,) as to permit of one of the 60 leaves B, provided with the sinuous opening, being slipped vertically downward. It will be understood that this is accomplished by forming a vertically-extending recess, b' , in the upper portion of the sinuous portion a^5 of the 65 bar on one side, and a similar recess, b^2 , in the lower portion of the other side of the sinuous portion of the bar. This may best be understood by reference to Fig. 2.

Each leaf B is slipped downwardly through 70 the recesses $b' b^2$ of the bar. When moved downwardly as far as possible, each leaf is moved laterally, or, in other words, in the direction of the length of the bar. When thus moved laterally beyond the recesses $b' b^2$, its 75 opening will engage with and slide along the sinuosities of the upper portion, a^5 , of the bar and interlock therewith. The leaves B so applied to the bar cannot be removed except by being severally moved lengthwise of the bar 80 to a position opposite the recesses $b' b^2$, whereupon they may severally be lifted upwardly off the bar.

I have shown the bar as provided with a master-leaf, B'. This master-leaf has an opening 85 which, as represented, differs from the opening in each leaf B in that it is straight-sided instead of having sinuous sides. This leaf is shown as made longer in a vertical direction, so as to extend below that part of the bar A 90 which it straddles. A lynchpin, C, is extended through the lower end of the leaf B' below the bar A. It prevents the leaf B' from being lifted off or removed in a vertical direction. The removal of the lynchpin will, however, 95 permit the detachment of the leaf B'. Any equivalent device may be employed instead of the lynchpin.

The sinuous or corrugated nature of the upper portion, a^5 , of the bar A not only serves 100

as a convenient and desirable means for securing the leaves B, but is also desirable because of the advantages it affords in respect to expansion and contraction occurring in the 5 structure.

What I claim as my invention, and desire to secure by Letters Patent, is—

1. The combination, with a grate-bar having an upper sinuous portion of uniform width or thickness, of leaves provided with sinuous 10 openings, substantially as specified.
2. The combination, with a grate-bar hav-

ing an upper sinuous portion of uniform width and thickness and recesses in the sinuous portion, of leaves provided with sinuous openings constructed to be inserted through the recesses and slid onto the sinuous portion to interlock therewith, and a master-leaf opposite the recesses, substantially as specified. 15

WILLIAM E. KELLY.
